DESIGN FOR AN AUTOMOBILE RADIATOR GUARD

Frank A. Neveu, Los Angeles, Calif.

Application October 11, 1932. Serial No. 45,315

Term of patent 14 years

To all whom it may concern:

Be it known that I, FRANK A. NEVEU, a citizen of the United States, residing at Los Angeles, in the county of Los Angeles, and State of California, have invented a new, original, and ornamental Design for an Automobile Radiator Guard, of which the following is a specification, reference being had to the accompanying drawing, forming a part thereof.

Figure 1 is a front elevation of an automobile radiator guard embodying my new design.

Figure 2 is a view in side elevation, the direc-

tion of view being indicated by arrow 2 of Figure 1.

The radiator guard embodying my new design is preferably constructed of metal, as by stamping it from sheet metal of not more than one-eighth inch in thickness, or by casting it of brass or other metal, and preferably of thickness not to exceed one-quarter inch.

I claim:

The ornamental design for an automobile radiator guard as shown and described.

FRANK A. NEVEU.
